UNITED STATES PATENT OFFICE.

WARREN L. SULLIVAN, OF NEWARK, NEW JERSEY, ASSIGNOR OF ONE-HALF TO ROBERT L. HATFIELD, OF NEWARK, NEW JERSEY.

SWITCHING-INDICATOR.

No. 893,757.

Specification of Letters Patent. Patented July 21, 1908.

Application filed October 3, 1907. Serial No. 395,737.

To all whom it may concern:

Be it known that I, WARREN L. SULLIVAN, a citizen of the United States, residing at 138 Monmouth street, Newark, county of Essex, 5 and State of New Jersey, have invented certain new and useful Improvements in Switching-Indicators, fully described and represented in the following specification and the accompanying drawings, forming a part of 10 the same.

This invention relates to a despatching system to facilitate the switching of railway trains from a main track or a section of single track to any one of a number of branches 15 leading from such section, and the object of the invention is to furnish a switching indicator for showing to the person or persons who operate the switches the number and the destination of the trains upon such track 20 section, so that the proper switch can be operated when the train reaches the desired branch, for directing it to its proper destination.

The apparatus described herein operates 25 to announce the approach of a train, to indicate the route it is intended to travel, and to permanently record the movements of the trains upon a given track section.

The apparatus described herein is not operated like block signals for indicating to a 30 train-driver whether or not the track which he is approaching is clear, and it is not therefore designed as a safety appliance, but as a means of avoiding delay in the despatch of 35 numerous trains from the same point. It is particularly adapted for a railway, (as in a subterranean tunnel) in which there is a piece of track over which all the trains travel in one direction for a certain distance and diverge therefrom upon different routes. It is a common practice upon railways operated 40 in this manner to indicate the route of different trains by the display of numbers or various colored lights upon the head of the train, but where several trains simultaneously approach the switchman within a contracted place, as in a tunnel, it is obvious that the switchman would be unable to determine the route of the second or third train until he 45 could see it, and if it was not convenient or possible to locate the switchman so that he could see such trains, considerable delay in traffic would result, as each train would have to be held up while the preceding one was 50 despatched, so that the operator could see

the following train before he operated the switch therefor.

The present invention provides the switchman with a switching indicator which, first, informs him how many trains are approaching upon the same track, second, the intended route of each train, third, the order in which they are coming, and fourth, makes a record of the number of trains, their destination, and their time-relation to one another. 60 With this apparatus, the switchman is in possession, long before the train reaches the switch, of all the information necessary for him to switch the train to its proper track, and considerable time can thus be saved in 65 handling a large number of trains. 70

The apparatus may be operated in connection with a section of track of any length, and embraces, first, an indicating device which shows the entrance of each train upon 75 the track-section, second, a magnet for moving the indicator-dial, which magnet is energized automatically or manually when the train enters the inlet of such section, third, a magnet operated by the train after it is 80 switched from the said section to reverse the operation of the indicating device, and fourth, a device to record the successive operations of the indicator.

I prefer to use for each branch-track an 85 indicating-dial capable of exposing a succession of similar marks, one for each of the trains (upon the track-section) intended for such branch. Such dial is readily made by a series of rotatable prisms having as many 90 sides, and one more, as there would be trains at any one time intended for such branch.

The prisms in each dial are arranged behind a vertical row of windows and connected to turn together. The prism at one end of 95 the row has a blank space upon one of its sides, and like indicating marks as *a*, *a*, *a*, upon the other sides, and the adjoining prisms in such series have a progressively greater number of blank sides and like indicating 100 marks upon the remaining sides, so that the first actuation of the prisms exposes one mark (as *a*) upon the first prism, but another actuation is required to expose a similar mark upon the second prism, and a third 105 actuation to expose a similar mark upon the third prism. The actuating magnet turns the prisms of one dial simultaneously step by step in one direction when each train enters the tunnel, and is actuated successively 110

when other trains for the same destination enter the tunnel, thus indicating upon the same dial how many trains for that destination are on the track section at once.

5 The reverse movements of the prisms (or other dial) are imparted by ratchet mechanism worked by the magnets referred to above and one complete apparatus, with the prism the ratchet mechanism and the magnets, is provided for each route or branch at the diverging end of the tunnel or track. These units constitute a switching indicator for the section of track, and may be arranged in groups of any number and contained in 10 one case or cabinet so as to be in convenient 15 view of the switchman.

To record the operations of the apparatus, a sheet of impresible material is conducted 20 past the core of the magnet which is operated as trains enter the tunnel, and an armature acting as a type or hammer is arranged adjacent to the core, so that each time the magnet is energized the paper is printed or 25 perforated. The sheet of paper may be fed by magnetically operated means in circuit 30 with the magnet which operates the hammer, or it may be fed by clock mechanism so as to indicate the time-relation between the successive 35 impressions, and of the trains which enter the track-section. Where this is not 40 convenient, the paper may be made wide enough to receive upon the same strip the 45 impressions produced by all the units in the system, and the succession of impressions 50 upon the paper then indicates the order in which the trains enter the tunnel. A time- 55 stamp may also be operated upon the paper to stamp the time upon the paper, simultaneously with the impressing device, either 60 with or without a stamped impression, to 65 show the time each train reported at the inlet of the track-section.

The invention will be understood by reference to the annexed drawing, in which 45 Figure 1 is a front view of the casing for an apparatus of five units adapted for a section 50 of track having five branches; Fig. 2 is a side view of the casing with the nearer wall removed, and the mechanism connected dia- 55 grammatically with a section of track and the circuit wires; Fig. 3 is a vertical section 60 on line 3—3 in Fig. 2, showing the connec- 65 tions for operating the rotating prisms; Fig. 70 4 is a plan of the stop-levers for the ratchet 75 armature, with the armature finger adjacent thereto; and Fig. 5 illustrates an indicator- 80 dial having a progressive series of marks 85 thereon.

The section of track *a* is shown with 60 branch-tracks *b*, *c*, *d*, *e* and *f*, which require 65 manually operated switches *a'*, *b'*, *c'*, *d'*, for 70 shifting the trains. The circuit wires *g* and *h*, shown in Fig. 2, are only those which 75 belong to one unit of the system in connection 80 with the branch-track *b*; but similar wires 85

would be included in each of the units which 90 is employed for each of the other branches *c*, *d*, *e* and *f*. For convenience, the track- 95 section may be referred to herein as a "tun- 100 nel".

The casing *i* contains the indicating and recording mechanism of the five units, including for each unit a magnet *j* connected with the circuit wires *g* from the inlet of the tunnel, a magnet *k* connected with the circuit wires *h* from a branch-track at the outlet of the tunnel, and an indicator having a dial formed of several prisms *l*, *m*, *n*, rotated simultaneously by pinions *o* and a rack *p*. The rack is moved in opposite directions by a 105 ratchet segment and pawls *q* which are actuated respectively by the magnets *j* and *k*. These pawls are mounted on armature-levers *r* jointed to the pivot *s* of the segment, and extend in opposite directions to engage 110 the ratchet teeth *t* upon the segment which carries an arm *u* jointed to the rack *p*. To permit the movement of the segment in either direction, the pawls *q* are held normally out of engagement, and the segment is 115 held from accidental movement by a brake- 120 spring *u* pressed into notches *t'* upon the segment. The energizing of either of the magnets *j* or *h* serves first to throw the pawl into the segment, and next to move the armature- 125 lever and shift the pawl and segment. This is effected as follows:

The armature-levers have armature-blocks 130 opposed to the cores of the magnets *j* and *k*, and the pawls *q* have also armature projections which lie between such blocks and the cores so as to be attracted first when the cores are energized. A stop-lever *y* is formed of bell-crank shape and pivoted adjacent to each of the magnets *j* and *k*, with one arm 135 having a stud *z* opposed to the free end of the armature-lever *r*, to hold the same from movement (when either of the magnets is energized) until the pawl is engaged with the teeth *t*. The other end of the stop-lever lies 140 in the path of the armature end of the pawl. The contact of such armature end of the lever with the stop-lever, throws the stop-lever out of line with the finger 1 upon the end of the armature lever, and permits the armature-lever then to move toward the magnet and 145 oscillate the segment by its attached pawl, its final movement retracting the pawl from the teeth *t*, leaving the segment free to be turned in the opposite direction. The energizing of the magnet *k* moves the segment to the right, as shown in Fig. 2, and turns the prisms to the left, as indicated by the arrow 150 4; while the energizing of the magnet *j* moves the segment reversely and turns the prisms to 155 the right, as indicated by the arrow 3.

The prisms show a plurality of like index 160 marks for a plurality of trains intended for the same branch, which is effected by making the lower prism with like marks upon three 165

sides and leaving one side blank. The prism next above is furnished with marks upon two sides and has two sides blank, while the upper prism has a mark upon only one side and has three sides blank. The adjoining prisms of the series have thus a progressively greater number of blank sides, and all the marks upon the remaining sides are similar in each dial, as indicated where the *f* appears at each 10 of the three windows in the column *f*. With this arrangement, the blanks upon the prisms are all presented to the windows 5 when no train is in the tunnel, and the index marks are so arranged upon the prisms that when 15 the prisms are first actuated the one at the end of the row or series shows a single index mark, while the others continue to show blanks. Upon a second actuation, which turns all the prisms one-quarter farther 20 around, the lower prism exposes a like mark, and the next higher prism also exposes a mark, thus showing by two similar marks at two of the windows 5 the presence of two trains intended for the same branch, as indicated in 25 Fig. 1 in the column *b*. During such rotation of the lower prism, the upper prism has continued to show blank faces to its window 5, but upon another actuation it presents a like index mark to the upper window, as in the column 30 5 of Fig. 1, showing the presence of three trains for the same branch. The passage of such trains from the tunnel over the same branch-track reverses the action of the prisms and diminishes the number of index 35 marks present, until only blanks are exposed to the windows. Each actuation of a pawl *g* gives the prisms a quarter turn or otherwise presents a single index mark or blank upon one side of the prisms, which is exposed at a 40 window 5 in the casing.

Fig. 1 shows two index marks exposed in column *b*, one index mark in column *c*, and three in column *f*, thus indicating the presence of six trains in the tunnel, but not showing 45 which train entered the tunnel first, nor which requires to be first despatched to its proper destination. These facts are shown by marks 18, made upon the recording sheet of paper 9, which is extended from a 50 reel 10 past the core of the magnet *j*, to feed-rolls 11 which move the paper step by step intermediate to the actuations of the magnet *j*. This is effected by the magnet 13 in circuit with the magnet *j* and having a 55 spring-moved pawl 12 fitted to ratchet-teeth upon one of the feed-rolls and retracted from such teeth by an armature 14. When the magnets *j* and 13 are energized, the pawl is retracted, and when they are 60 deenergized the spring-moved pawl turns the feed-roll a suitable distance. The magnets *j*, shown in Fig. 1, lie in a row below the several columns of windows *b*, *c*, *d*, *e* and *f*, and the casing *i* is made with a glass 65 pane 15 adjacent to the paper below the

said magnets, with lines 16 ruled upon the glass which would be numbered from the top downwardly in correspondence with the movements imparted to the paper by the feed-rolls. When the magnet *j* of any unit 70 is energized, a printed mark, puncture or other impression 18 is made upon the paper by a hammer 17, which is formed as an armature adjacent to the paper opposite such magnet, and is shown with a point in 75 Fig. 2 to perforate the paper. The train first entering the tunnel produces a puncture in the paper in a line below one of the windows 5, as at the impression 18 below the column *f*, and thus shows that the first 80 train approaching the operator is to be despatched to the branch-track *f*. The destination of the next train is shown by the location of the impression next above upon the paper, as at the impression 18 in column 85 *b*. The impression next above is in the column *c* showing that the next train should be despatched to that branch, and in like manner the disposition of the successive impressions upon the paper shows 90 the destinations of the successive trains. At the end of a given term, the sheet of paper may be severed and preserved as a record of the trains despatched during such term, the record showing the order in which 95 the trains for the several branch-tracks entered the tunnel. The time-relation of the trains can also be shown by the application of a time-stamp 22 to impress the paper at regular intervals, or with each 100 actuation of the magnet *j*.

A generator 6 is shown in each of the circuits *g* and *h*, and an electric contact 8 is shown near the inlet of the tunnel to be operated manually or automatically when 105 any train enters the track-section, for despatch to the branch-track *b*. This energizes the magnet *j* in that unit of the case *i* and turns the dial or indicator which corresponds with the branch-track *b*. Such indication shows the presence in the tunnel 110 of a train intended for that branch, and contacts 7 are shown upon the rails of this branch-track *b* which would be connected by the car axle as it passes over the contacts, thus closing the circuit through the magnet *k* and reversely operating the dial so as to withdraw or diminish the indication as each train leaves the tunnel. A corresponding unit of the apparatus is provided 115 for each of the branch-tracks, there being a contact 8 at the inlet of the track-section for each of the branches, and a separate indicator for each of the branch-tracks, as is clearly shown in Fig. 1, where the apertures for exposing the index marks are arranged in vertical columns marked *b*, *c*, *d*, *e* and *f*, in correspondence with the branch-tracks.

In Fig. 1, index marks *b* appear from the 120

lower and middle one of the three prisms, and to indicate such marks in Fig. 2, projections are shown upon corresponding sides of the prisms, and similar projections are 5 shown upon two other sides of the bottom prism, while the upper prism has only one such projection or index mark. Any number of prisms may be used corresponding with the greatest number of trains that would 10 be present in the tunnel at one time for a given branch. Instead of using a plurality of such indicating devices to form an indicating dial, a single dial-piece such as the segment 19 in Fig 5 may be provided with a 15 plurality of progressively increasing index marks 21, and such single piece actuated by an arm 20 connected with a rod p' from the ratchet-segment.

In Fig. 5, two index marks or projections 20 upon the segment 19 are shown opposite the window 5, and if the segment were turned upwardly three would be shown. If the segment were turned downwardly one step, one projection would be shown, and if 25 turned downwardly two steps a blank would be presented to the window.

From the above description it is obviously immaterial what form of dial mechanism be employed to indicate the number of trains, 30 provided it is capable of being operated reversely so as to advance or retract the index marks, as may be desired.

When the dial is constructed with a plurality of prisms as shown, it will be understood that the prisms have like index marks 35 upon certain of their sides in a progressive order, so that the mark first exposed may be repeated when the first prism is again turned, and the remaining sides are unprovided with 40 marks so as to make no indication until the prisms below it have been sufficiently turned. With this construction, the simultaneous turning of the prisms presents successively an increasing number of like marks, 45 and their rotation in the opposite direction correspondingly decreases the number of indicating marks presented.

Only one of the feeding-magnets 13 is shown, and is represented in Fig. 1 at one end 50 of the feed-rolls d , and such a single magnet suffices to feed the paper by connecting it in circuit with all the magnets j of the different units in the same case.

I am aware that in signaling apparatus 55 for electric railways various kinds of indicators are used which are actuated by ratchet-mechanism and are capable of being operated in reverse directions. I do not therefore claim merely a reversible indicator, but the provision of such an indicator for each one of several branch-tracks connected with a single line of track, to guide the switchman in despatching the trains to the required branch-tracks.

Having thus set forth the nature of the invention what is claimed herein is:

1. In a switching indicator for showing the number and destination of a series of trains upon a track-section having branch-tracks at its exit end, the combination, with 70 a casing having a vertical row of windows for each of such branch-tracks, with prisms having blank sides and indicating marks as set forth behind each row of windows, of means for turning the prisms step by step 75 progressively in either direction to indicate the number and destination of the trains, and manually operated switches for switching the trains from the railway section to the respective branch-tracks.

2. In a switching indicator for showing the number and destination of a series of trains upon a track-section having branch-tracks at its exit end, the combination, with a casing having a vertical row of windows for 85 each of such branch-tracks with a series of prisms having blank sides and indicating marks as set forth behind each row of windows, connecting means for rotating each series of prisms independently, a magnet for 90 each of such series of prisms with a circuit operable at the inlet end of the railway section and means to turn the prisms in one direction, and an additional magnet for each 95 of such series of prisms with a circuit and a contact operated automatically by the train passing over one of the branches, to turn the prisms in the opposite direction, and means for manually operating the switches in accordance with the index-marks exposed.

3. In a switching indicator for showing the number and destination of a series of trains upon a track-section having branch-tracks at its exit end, the combination, with a casing having a vertical row of windows for each 105 of such branch-tracks, of indicating mechanism arranged behind each row of windows for one of such branch-tracks, and comprising a series of horizontal prisms journaled one above another behind the several windows and connected to turn simultaneously, the prism at one end of the row having a blank space upon one side and like indicating marks upon the other side, and the adjoining prisms in such series having a progressively greater number of blank sides, and like indicating marks upon the remaining sides, a magnet with a circuit and manually operated contact at the inlet end of the track-section with connections to turn the prisms 110 step by step in one direction to successively expose their indicating marks, and a magnet with a circuit and contact operated automatically by a train passing over one of the branches and connections to turn the prisms 115 step by step in the opposite direction to progressively expose the blank spaces thereon.

4. In a switching indicator for showing the

destination of a train as it approaches a switch, the combination, with a section of railway track having railway branches at its exit end with switches for shunting the trains

dials, and means for impressing the sheet at each actuation of a dial and thereby indicating the relation of such actuations to one another. 55

- 5 to the said branches, of unitary signaling devices, one for each of said branches, having each an indicator-dial with a series of index-marks thereon, a magnet with an electric circuit having a contact operable at the inlet 10 end of the railway section, and a magnet with electric circuit operable upon one of the branches, mechanism connected with the two magnets for turning the said dial step by step in reverse directions, and means for 15 manually operating the switches of the branch-tracks in accordance with the indications of the dial.

8. In a signaling apparatus, the combination, with an indicator-dial having a series of index-marks, of mechanism having means to operate in reverse directions upon the 60 said dial, a section of railway-track, a magnet with circuit having a contact operated at the inlet of the section to operate the dial in one direction, a magnet with circuit automatically operated at the outlet of the section to operate the dial in the opposite direction, a sheet of paper with a magnet for shifting the same intermediate to the operations of the first mentioned magnet, and means for impressing the paper at each 65 actuation of the first mentioned magnet, whereby the entrance of each train upon the track-section is recorded upon the paper.

5. In a switching indicator for showing the number and destination of a series of trains 20 upon a track-section having branches at its exit end, the combination, with a section of railway track having railway branches at its exit end and with switches for shunting the trains to the said branches, of an indicator-dial for each of said branches and a series of index-marks thereon, a magnet for each of said dials with a circuit and a contact at the inlet end of the railway section to close such circuit and turn the dial in one direction, a 25 magnet for each of said dials with a circuit and a contact operated automatically by a train passing over one of the branches to close the said circuit and turn the corresponding dial step by step in the opposite direction, and manually operated switches for 30 directing the trains in accordance with the indications of the dial.

9. In a switching indicator, a dial comprising a casing with a row of windows, a 75 plurality of prisms mounted to rotate behind the windows and having like index-marks upon certain of their sides as described, and the remaining sides unprovided with marks, and means for turning the prisms simultaneously, whereby the prisms present successively at the different windows an increasing 80 number of like marks.

6. In a signaling apparatus, the combination, with a plurality of indicator-dials having each a series of index-marks, of means for turning each of the dials step by step progressively in either direction, and means for recording the successive actuations of the several disks in a time-relation to one another. 45

10. In a switching indicator, a dial comprising a casing with a row of windows, a 85 plurality of prisms mounted to rotate behind the windows and having like index-marks upon certain of their sides as described, and the remaining sides unprovided with marks, and means for turning the series of prisms 90 simultaneously in either direction, whereby the turning of the prisms in one direction presents an increasing number of like marks and their rotation in the opposite direction correspondingly decreases the number of marks 95 presented.

In testimony whereof I have hereunto set my hand in the presence of two subscribing witnesses.

WARREN L. SULLIVAN.
